UNITED STATES PATENT OFFICE

113,574

DESIGN FOR A SHOE

Otto Schwartz, St. Louis, Mo.

Application January 3, 1939, Serial No. 82,133

Term of patent 3½ years

To all whom it may concern:

Be it known that I, Otto Schwartz, a citizen of the United States of America, residing in the city of St. Louis and State of Missouri, have invented a new, original, and ornamental Design for a Shoe, of which the following is a specification, reference being had to the accompanying drawing, forming part thereof.

Fig. 1 is a plan view of a shoe showing my new design.

Fig. 2 is a side elevational view thereof.

I claim:

The ornamental design for a shoe, substantially as shown.

OTTO SCHWARTZ.
